ATTORNEYS

UNITED STATES PATENT OFFICE.

OWEN T. LAPHAM, OF CLEVELAND, OHIO.

WRINGER.

SPECIFICATION forming part of Letters Patent No. 245,638, dated August 16, 1881.

Application filed March 25, 1881. (Model.)

To all whom it may concern:

Be it known that I, OWEN T. LAPHAM, of Cleveland, in the county of Cuyahoga and State of Ohio, have invented certain new and useful 5 Improvements in Wringers; and I do hereby declare the following to be a full, clear, and exact description of the invention, such as will enable others skilled in the art to which it pertains to make and use it, reference being had to the accompanying drawings, which form part of this specification.

My invention relates to clothes-wringers; and it consists in certain features of construction and combinations of parts, as will hereinafter be explained, and pointed out in the 15 claims.

In the drawings, Figure 1 is an isometric view of my wringer. Fig. 2 is a vertical section of the same.

20 A represents the frame. B B' are the rolls. C is a shaft, which is made preferably of wood. This shaft is provided with three cams, one at each end, c c, for operating the tension of the rolls B B', and one in the center, a, operating the clamping device. The center cam, a, is provided with a handle or lever, D, for operating the shaft C and its cams. This handle, in turn, is provided with a projection or lug, d.

25 E is the clamping-frame, which is provided at its upper end with a cross-piece, F. This clamping-frame E is fastened to the frame A by means of a bolt, H, which passes through said frame A, and also through the clamping-frame E. This bolt H is provided with a thumb-nut, I, which acts as an adjustable fulcrum for the clamping-frame E.

30 e is a spring, which may be of wood or metal, the ends of said spring engaging with the cams c c, and the center resting on the cross-bar i, the ends of said cross-bar i, in turn, resting upon and operating the journals of the upper roll.

The operation of the clamping device is as 45 follows: When it is desired to use the wringer the legs of the frame A are placed inside of the tub, and the legs of the clamping-frame E are placed outside the shaft C, and its cams c c and a are revolved in the direction of the arrow in Fig. 2 by means of the lever or handle D, which brings the cam a in contact with the cross-bar F, and operates to push the upper end of said clamping-frame E out, and hence the lower part or legs are forced in and grasp

55 the side of the tub between them and the legs of the frame A. At the same time that the cam a operates the clamping-frame E the cams c c, coming in contact with the ends of the spring e, operate, through said spring e, the bar i, and the journals of the roll, to force 60 the top roll against the lower one. When it is desired to unclamp the wringer from the tub it is obvious that the act of unclamping will relieve the rolls from any tension. The lug or projection d on the handle D, coming 65 in contact with the outside of the bar F, operates to draw the top of the clamping-frame E in, and hence force the legs out and relieve the tub from their grasp.

I may provide the top of the legs of the 70 clamping-frame with a spring, either of metal or rubber, which acts to keep the wringer in place on the tub before it is clamped by means of the cam a, without the necessity of the operator holding it there.

75 It will be seen that the cam a, after it has operated to clamp the machine to the tub, will not act to further force the upper part of the clamping-frame E out; but the cams c c, as they are revolved further, will act to increase 80 the tension of the rolls.

I may also provide the lower part of the legs of the clamping-frame with springs l, which will act to force the said lower part of the legs out when the cam a releases the cross-bar, and 85 bring said cross-bar in position to be operated upon by the lug d.

What I claim is—

1. In a clothes-wringer, the combination, with the wringer-rolls and clamping-frame, of 90 a rock-shaft journaled in the frame of the wringer, said rock-shaft provided with a cam that engages with the clamping-frame, and cams which engage with the tension-springs of the wringer-rolls, substantially as set forth. 95

2. In a clothes-wringer, the combination, with the clamping-frame provided with cross-bar F and spring l, of the rock-shaft C, provided with handle D and lug d, substantially as set forth.

100 In testimony whereof I have signed my name to this specification in the presence of two subscribing witnesses.

OWEN T. LAPHAM.
